W. BURSTYN

SOLDERING IRON

Filed Feb. 6, 1923

W. N. BURSTYN
Witness: W. H. HARRIS

UNITED STATES PATENT OFFICE.

WALTHER BURSTYN, OF BERLIN, GERMANY.

SOLDERING IRON.

Application filed February 6, 1923. Serial No. 617,411.

To all whom it may concern:

Be it known that I, WALTHER BURSTYN, a citizen of Germany, residing at Berlin, Prussia, Germany, have invented a new and 5 useful Soldering Iron, of which the following is a specification.

My invention relates more particularly to soldering irons in which a flame of gas is used to heat continuously the copper piece. 10 Hitherto gas mixed with air has been burned in such soldering irons, the mixture being produced either by an injector (Bunsen burner) or by means of an air blast.

According to the present invention a very 15 simple and effective soldering iron is produced by the use of a special burner which has remarkable advantages in comparison with the above mentioned burners. This burner is fed by ordinary gas and the flame 20 is made hot and effective by its special shape hitherto not used for heating purposes.

When pure gas burns out of a round hole 25 a longish pointed flame is obtained which is bright, sooty and not very hot if the diameter of the hole surpasses a certain small size corresponding to a consumption of about 10 litres of gas per hour, assuming that a gas of usual pressure and composition 30 is employed. But if means are provided to produce a thin, flat and approximately semi-circular flame like the flames in ordinary acetylene lamps the flame is under the same conditions non-luminous and 35 very hot up to a consumption of 50 or 80 litres per hour, according to the pressure and composition of the gas. This effect is due to the thin shape of the flame which offers to the air a relatively large surface, 40 thereby producing favourable conditions of combustion.

The object of the present invention is a soldering iron fitted with one or more burners producing a flame of the described shape. 45 Two-hole burners such as are used for acetylene are preferably used for this purpose.

In the accompanying drawing, Figures 50 1 and 1^A are, respectively, a side elevation and a vertical section of a burner tip embodying the invention;

Fig. 2 is a side elevation, partly in section, of one form of soldering iron;

Figs. 3 and 3^A are, respectively, a fragmental side elevation and a fragmental end 55

elevation of a slightly modified form of iron with three burner openings;

Figs. 4 and 4^A are similar views of a further modification with six burner openings; 60

Fig. 5 is a fragmental side elevation of a still further modified form of iron.

Referring to Fig. 1, there is illustrated one of the tips *b*, preferably made of soap stone. The gas comes out of two tiny holes *xx*, the two gas jets hitting one another at an angle of about 90° and thereby producing a thin flat flame in form of a semicircle ("butterfly-flame"), the plane of which stands perpendicular to the plane of the 70 two holes.

The advantage in comparison with a Bunsen burner lies in the fact that the burner is simpler and shorter, and that the flame produces a more concentrated heat and will 75 not flutter or jump and, being very stiff, but is able to burn in any position that the iron is held. The advantage compared with a soldering iron using compressed air lies also in the greater simplicity of construction, 80 and in the fact that the air blast plant is dispensed with and that the heat of the flame is better utilized owing to the relatively small speed of the flame gases consequently having more time to supply their 85 heat to the copper piece.

One simple flame as described is sufficient for light soldering irons; for heavier soldering irons a number of burner tips have to be used being placed sufficiently apart from 90 each other.

In Figs. 2-5, *k* represents the copper piece of the soldering iron, *b* a burner top made of soap-stone or metal, *p* the burner in which one or several burner tips are cemented, *t* a metal gas tube serving at the same time as handle to the soldering iron and as passage for the gas which is conducted to it by a flexible tube *e*, usually made of india rubber. 95

Fig. 2 shows a small soldering iron in form of a hammer with one single flame. The copper piece *k* is cylindrical and its front is chisel-shaped. It is fixed to the burner *p* by means of a support *i*. An asbestos-washer *a* lessens diversion of heat. Gas tube *t* is screwed into the burner *p* 105 and is mounted on its other end with a piece *r* for the india rubber tube *e*. A wooden handle *h* is fixed on the gas tube. 110

A heavier soldering iron of similar construction with 3 burner openings is shown in Fig. 3. The support *i* is provided with a slit *c* in order to adapt the iron to the varying gas pressure by altering the distance between burner and copper piece.

Fig. 4 shows a heavy soldering iron with six burner openings arranged in two rows. The copper piece, of square section, is supported by two pillars *i*. The burner piece *p* contains the necessary holes to conduct the gas to the six burner openings.

Fig. 5 represents a small soldering iron of pointed shape and square section with one flame.

For many purposes stationary soldering irons are wanted. In this case the tube *t* may be connected rigidly with the gas supply.

While the preferred embodiment of the present invention has been specifically illustrated and described, it is to be understood that the present invention is not limited to the illustrated embodiment but may be embodied in other constructions of soldering irons for gas within the scope of the invention as particularly pointed out in the following claims.

What I claim as my invention is:

1. In a soldering implement, a metal burner member formed with an internal passage to receive a supply of illuminating gas, said passage terminating in an opening; and a burner tip of refractory material seated in said opening and formed solely with two diverging internal, gas-receiving apertures opening at their outer ends through the inner face of the tip, and two oppositely-located, converging holes of appreciably smaller diameter than said apertures leading from the inner ends of the latter and opening in extremely close relation to each other at their outer ends through the outer face of said tip, whereby the burning gases issuing through said converging holes will

impinge against each other and unite in forming a thin, flat flame which is non-luminous and extremely hot.

2. A burner tip of refractory material for gas-heated soldering implements, formed solely with two diverging internal, gas-receiving apertures opening at their outer ends through the inner face of the tip, and two oppositely-located, converging holes of appreciably smaller diameter than said apertures leading from the inner ends of the latter and opening in extremely close relation to each other at their outer ends through the outer face of said tip, whereby the burning gases issuing through said converging holes will impinge against each other and unite in forming a thin, flat flame which is non-luminous and extremely hot.

3. In a soldering implement, a metal burner member formed with an internal passage to receive a supply of illuminating gas, and with a plurality of parallel, longitudinal rows of openings with which such passage communicates, the openings in the several rows being arranged in transverse alignment; and a burner tip of refractory material seated in each opening, each tip being formed solely with two diverging internal, gas-receiving apertures opening at their outer ends through the inner face of the tip, and two oppositely-located, converging holes of appreciably smaller diameter than said apertures leading from the inner ends of the latter and opening in extremely close relation to each other at their outer ends through the outer face of said tip, whereby the burning gases issuing through said converging holes will impinge against each other and unite in forming a thin, flat flame which is non-luminous and extremely hot.

In testimony whereof I affix my signature.

DR. WALTHER BURSTYN.
